RELAY INSTRUMENT

Filed June 18, 1930

UNITED STATES PATENT OFFICE

IVAN I. EREMEEFF, OF PHILADELPHIA, PENNSYLVANIA, ASSIGNOR TO THE BROWN INSTRUMENT COMPANY, OF PHILADELPHIA, PENNSYLVANIA, A CORPORATION OF PENNSYLVANIA

RELAY INSTRUMENT

Application filed June 18, 1930. Serial No. 461,934.

The general object of my present invention is to provide a potentiometer measuring instrument with improved means characterized by their relative simplicity and effectiveness 5 for performing operative functions heretofore effected in such instruments by the use of more complex mechanism.

More specifically the object of the present invention is to provide improved means for 10 adjusting the potentiometer instrument exhibiting means, which may comprise an indicator or recording element, and usually comprises both of such elements, and for adjusting the point of engagement of the main 15 potentiometer slide wire resistance and its cooperating contact, when the deflections of a galvanometer associated with the potentiometer indicate the necessity for such adjustments.

20 The various features of novelty which characterize my invention are pointed out with particularity in the claims annexed to and forming a part of this specification. For a better understanding of the invention, 25 however, and the advantages possessed by it, reference should be had to the accompanying drawing and descriptive matter in which I have illustrated and described a preferred embodiment of the invention.

30 Of the drawing:—

Fig. 1 is a perspective view of a potentiometer instrument with parts broken away and removed to render other parts of the instrument more readily visible;

35 Fig. 2 is a sectional elevation of a portion of the apparatus shown in Fig. 1; and

Fig. 3 is a perspective view illustrating a modification of a portion of the apparatus shown in Fig. 1.

40 In Fig. 1 I have shown a recording potentiometer instrument in which a preferred form of the present invention is embodied. The instrument shown in Fig. 1 comprises a feed roll A' carried by a shaft A for advancing a record strip a, which is drawn by the roll A' from a record strip supply roll A⁵. A record is formed on the record strip a by a pen b supported by a pen carriage B. The latter comprises a sleeve portion B' surrounding a pen carriage supporting and ad-

justing shaft C which extends parallel to the feed roll shaft A. The shaft C is formed with a helical groove C' receiving a tooth portion B² of the sleeve B' which in effect is a nut threaded on the shaft C and is moved longitudinally of the shaft C by the rotation of the latter. The pen carriage B also supports a contact member BR which engages the main potentiometer slide wire resistance r. The latter is in the form of a helix coiled about and supported on a drum R' carried by a shaft R parallel to the feed roll shaft A.

As shown, the pen carriage B is so disposed that it is held by gravity in the position in which the contact BR engages the resistance r, but additional guiding means may be provided for more positively holding the carriage in the position in which the contact BR engages the resistance r, if considered necessary or desirable.

The shafts R and C are geared together. The connecting gearing in the form shown, includes a gear C² secured to the lefthand end of the shaft C, a gear R² secured to the left-hand end of the shaft R, and an intermediate gear M in mesh with the gears C² and R². The rotative speeds of the shafts R and C, and the pitches of the helical slot C' and of the helically wound slide wire resistance r are advantageously so related that when the shafts 70 R and C are rotated, the longitudinal movement given the contact BR is the same as would be given the contact if the latter were moved by the screw action of the helically wound resistance r. In consequence, when the shafts R and C are rotated, the relative movement of the contact BR and the resistance r is in the longitudinal direction of the portion of the latter in engagement with the contact.

The feed roll shaft A is driven from a constantly rotating shaft D by gearing shown as comprising gears D' and A² secured to the shafts D and A, respectively, and an intermediate idling gear A³. The shaft D which is the main drive shaft of the instrument and gives motion, as hereinafter described, to the shafts C and R as well as to other operative parts of the mechanism, is continuously rotated in the clockwise direction and at a suit-

55

100

able speed by a synchronous motor E which in practice may well be of the type of well known Warren electric clock motor.

The shafts A, A⁵, C, D, and R, gears M, 5 MA and A³, and other parts hereinafter mentioned, are journalled in the side plates X forming a part of the supporting framework of the instrument. As shown in Fig. 1, the major portion of the left hand supporting 10 plate X is broken away so as not to obscure adjacent portions of the mechanism. The driving motor E for the main drive shaft D is mounted on the right hand frame plate X. The shafts R and C are periodically adjusted 15 angularly in one direction or the other in accordance with the deflection from its neutral position of the pointer F' of the galvanometer F forming a part of the potentiometer instrument. The mechanism by 20 which such adjustments are effected includes means for periodically clamping the galvanometer pointer F' in the position which it then occupies, and the engagement of the pointer when so clamped by a selective actuating element of the adjusting mechanism. The periodic clamping of the galvanometer pointer is effected by means of a depressor cam d carried by the constantly rotating shaft D and serving to depress a clamping 25 element G so that the pointer will be gripped between the element G and the straight edge H forming the bottom wall of a slot in a stationary plate H' supported by the instrument framework and through which the free 30 end of the pointer F' projects. The element G advantageously, and as illustrated, is in the form of a spring plate, the resiliency of which holds the plate above the path of deflection of the pointer F' except when the 35 plate is depressed by the cam d.

The adjusting mechanism comprises a rock shaft I above and generally parallel to the pointer F' when the latter is in its neutral position, a clutch disc I' secured to the rock shaft I, an arm I² pivotally mounted on the rock shaft I, and a pawl member i which is pivotally connected at i' to the arm I² and forms a pointer engaging extension of the latter. The member i includes a detent portion i² which is normally urged by a spring i³ into the position in which it engages the periphery of the clutch disc I' and thus locks the member i, arm I² and the rock shaft I rigidly together. When the rock shaft I is rotated 45 in the counterclockwise direction, as herein-after explained, to bring the member i into engagement with the galvanometer pointer F', the latter then being clamped between the member G and straight edge H, the spring i³ yields to permit the turning movement of the member i and arm I² to be interrupted without interrupting the rotative movement 50 of the shaft I. As soon as the reverse movement of the shaft I begins the detent i² again

locks the arm I² and member i to the rock shaft I.

The rock shaft I is given periodic turning movements in the counterclockwise direction by the shaft D through mechanism comprising a segmental gear D² carried by the shaft D, a cooperating spur gear K' carried by a shaft K parallel to the shaft D, and an operative connection between the shafts K and I. In the construction shown in Fig. 1 75 the shafts K and I are operatively connected by a worm K² carried by shaft K, and a worm gear I⁵ carried by the shaft I and in mesh with the worm K². To avoid lost motion the mounting for the shaft I is preferably arranged to press the gear I⁵ snugly against the worm K². A spring I¹⁰, shown as loosely coiled about the shaft I and having one end secured to the shaft and the other to the instrument framework, forms an additional 80 means for preventing lost motion.

Associated with the shaft K is a spring K⁵ which yieldingly opposes the movement imparted to the shaft K by the shaft D through the gears D² and K' and which when permitted so to do returns the shaft K and thereby the shaft I to their normal positions. As shown, the spring K⁵ is a helical spring loosely coiled about the shaft K and having one end secured to the gear K', and its other end anchored to the instrument framework. The normal position of the shaft K which is that shown in Fig. 1, is fixed by the engagement of a stop arm K⁶ carried by the shaft K with a stationary stop shown as a projection H² 100 from the plate H'.

The shaft K carries at its opposite ends selector cams L and LA. The angular positions assumed by these cams at one stage in the operation sequence following each rotative movement imparted to the shaft K by the shaft D, determine the angular adjustment, if any, then given to the pen carriage supporting shaft C and to the slide wire resistance supporting shaft R. Whenever the gear D² engages the gear K', the shaft K is thereby rotated through an angle which may well be 300° or so, before the continued rotation of the shaft D moves the mutilated gear segment D² out of engagement with the gear K'. The rotative movement thus imparted to the shaft K gives a corresponding rotative movement to the shaft I. The arm I² and the pawl member i turn with the shaft I until the member i engages the galvanometer pointer F' which is then clamped between the member G and straight edge H. When the member i engages the pointer F' the spring i³ yields and permits just enough turning movement of the member i about its pivot i', to disengage the clutch disc I' so that the latter and the shaft I may continue their rotative movements without carrying the arm I² and member i with them. The part i, as shown, is so formed and disposed that it has 115

a gravitational tendency to engage the pointer F' in any position of the latter.

As soon as the gear D² passes out of engagement with the gear K' the shaft K starts to turn in the reverse direction under the action of the spring K⁵, and this rotative movement of the shaft K effects a corresponding reverse rotation of the shaft I. The rotative movement of the latter, and thereby the rotative movement of the shaft K, is interrupted when the pawl member i engages a projection G⁶ on the member G.

The positions of the cams L and LA at this time determine the extent and direction for angular adjustment of the shafts C and R, and are dependent upon the then position in which the galvanometer pointer F', has been clamped because the latter fixes the angular relation of the arm I² and the clutch disc I'. When those parts are relocked at the beginning of the return movements of the shafts K and I. The greater the deflection of the pointer F' to the right, as seen in Fig. 1, the greater will be the angular movement permitted the arm I² and the pawl member i before the latter engages the pointer, and the greater will be the return movement of the shafts I and K occurring before the pawl member i engages the stop G⁵ and thereby arrests the return movements of the cams L and LA.

After the adjustments of the shafts R and C required by the positions of the cams L and LA are effected, the continued movements of the shaft D and cam d release the member G which rises and releases the galvanometer pointer F'. The rising movement of the member G raises the stop G⁵ and thus permits a further slight movement of the pawl member i under the action of the spring K⁵.

The movement then permitted the pawl member i is sufficient to bring the spur i² of the pawl member against a stop H³. This turns the member i about its pivot i' sufficiently to disengage the detent i² from the periphery of the clutch disc I', and thereby permit the shafts I and K to then complete their return movements to their normal positions in which the stop arm K⁶ carried by the shaft K engages the stationary projection H². When the clamped member G is next depressed by the cam d, the projection G⁶ cams the pawl member i in the counter-clockwise direction sufficiently to separate the spur i² from the stop pin H³, and thereby permits the spring i² to force the detent i² into locking engagement with the clutch disc I'.

During each period in which the return movement of the shaft K is temporarily interrupted by the engagement of the member i with the stop G⁵, the mechanism collectively controlled by the cams L and LA effects whatever adjustments of the shaft C and R

are required by the then position of the galvanometer pointer F'. The cam L controls the adjustment in the counter-clockwise direction of the shafts R and C which is required when the galvanometer pointer F' is clamped in a position at the right of its neutral position. With such galvanometer pointer position, the return movement of the shaft K will be temporarily arrested by the engagement of the pawl member i with the stop G⁵, with the cam L in such position that the projection N' of a pawl member N will then engage the cam at some point along the rising portion L', L², L³ of the cam periphery. The distance between a point on the periphery of the cam L and the axis of the shaft K progressively increases with the angular distance in the clockwise direction of that point from the point L'.

The pawl member N is pivoted on a pawl lever m journaled on the supporting shaft for the intermediate gear M connecting the gears C² and R² at the left hand side of the instrument as shown in Fig. 1. A spring N⁵ having one end connected to the member N and having its other end connected to the instrument frame-work, constantly tends to hold the detent N² of the member N in engagement with the periphery of a clutch disc M' secured to the gear M, except when the upper portion of the member N is moved to the left, as seen in Fig. 1, slightly in excess of the amount required to move the lever m into engagement with the stationary stop A¹⁰, whereupon the detent N² is turned away from the disc M'. As soon as any return movement of the upper portion of the member N to the right is permitted, the detent N² turns into operative engagement with the clutch disc M'.

A cam DN secured to the left hand end of the shaft D periodically engages a projection N³ of the member N and moves the pawl and thereby the pawl lever m in the counter-clockwise direction. This movement of the pawl and pawl lever does not impart a corresponding movement to the gear M. The movement in the counter-clockwise direction thus imparted to the pawl member N occurs during the period of operation preceding the initial return movement of the shaft K, and is just sufficient to separate the projection N' from the shaft K by a radial distance equal to the distance from the shaft to any point along the dwell portion L³, L⁴, L⁵ of the cam L. Immediately after the initial return movement of the shaft K is completed, the continued movement of the cam DN permits a return movement of the pawl N if the position of the cam L then permits such return movement.

If the position of the cam L is then such that its dwell portion L³, L⁴, L⁵ is in contact with the projection N', no return movement of the pawl N can occur. If, however,

the rising portion L' , L^2 , L^3 of the cam L is then between the shaft K and the projection N' , the spring N^5 effects whatever return movement of the pawl N is required to bring 5 the projection N' into engagement with the periphery of the cam L at the juxtaposed point along the rising portion L' , L^2 , L^3 of the cam.

Such return movement rotates the gear M 10 in the clockwise direction, and thereby gives counter-clockwise rotations to the slide wire resistance supporting shaft R , and to the pen carriage adjusting shaft C . The magnitude of those rotative movements depends upon 15 the distance from the shaft K of the point along the rising portion L' , L^2 and L^3 of the cam L engaged by the pawl projection N' . The rotative movement of the shaft R rebalances, or tends to rebalance the potentiometer, 20 and the adjustment of the pen carriage C corresponds to the increase in the value of the quantity measured indicated by the deflection of the galvanometer pointer into the position in which the latter was clamped 25 previous to the adjustment.

When the galvanometer pointer is clamped in a position at the left of its neutral position, indicating the necessity for a clockwise adjustment of the shafts R and C , the position 30 of the cam L is such as to hold the detent N^2 of the pawl N out of engagement with the clutch disc M , but the position of the cam LA is then such as to permit the devices controlled by it to effect the proper clockwise 35 adjustments of the shafts R and C . The devices through which the cam LA thus controls clockwise adjustments of the shafts R and C comprise parts N , N' , N^2 , N^3 , N^4 , m , M , M' and DN , at the right hand side of the 40 instrument, which may be counterparts of the correspondingly designated parts associated with the cam L . The intermediate gear M at the right hand side of the instrument, however, gives movement to the shaft R through 45 the shaft C , and the gears C^2 and M at the left hand side of the instrument. Furthermore, since the gear M at the right hand side of the instrument is connected to the shaft C through the gear C^{20} and an intermediate 50 idling gear MA , the clockwise adjustments given to the gear M at the right of the instrument, give counterclockwise rotative movements to the shaft C , and to the shaft R . The cam LA may be a counterpart of the cam L , 55 but is angularly displaced with respect to the latter about the shaft K through an angle of 180° .

In the modification illustrated in Fig. 3, the worm and gear connection between the 60 shafts I and K illustrated in Fig. 1, is replaced by a side cam K^{10} secured to the shaft K and engaged by a cam roller I^{11} carried by an arm I^{12} secured to the shaft I . The side 65 of the cam K^{10} engaged by the roller I^{11} is oblique to the axis of the shaft K , and as the

latter is rotated out of its neutral position the cam K^{10} acting through the roller I^{11} and arm I^{12} gives a counterclockwise rotation to the shaft I in the same manner as the shaft I is rotated through the worm K^2 and gear I^5 in 70 the construction shown in Fig. 1. The spring I^{10} acting on the shaft I holds the roller I^{11} against the cam K^{10} at all times and lost motion is thus eliminated.

In the operation of the instrument disclosed 75 it is to be noted that while each selective effect depends in a certain general sense upon the position of the pawl member i on each engagement of the latter with the pointer F' , in a more specific sense each selective effect is produced by and is dependent directly upon the magnitude of displacement of the member I , when in engagement with the pointer F' from the stop G^6 . Each adjustment of the shaft R occurs after the completion 80 of the return movement of the member i from its position of engagement with the pointer F' into its position of engagement with the stop G^6 , and depends upon the magnitude of that movement. 85

While in accordance with the provisions of the statutes, I have illustrated and described the best forms of my invention now known to me, it will be apparent to those skilled in the art that changes may be made in the form of the apparatus disclosed without departing from the spirit of my invention, as set forth in the appended claims, and that in some cases certain features of my invention may be used to advantage without a corresponding use of 90 other features. 100

Having now described my invention, what I claim as new and desire to secure by Letters Patent is:—

1. The combination with a deflecting element, of a member extending through the plane of deflection of said element and movable along the deflection path of a portion of said element into and out of engagement with said portion, means for periodically moving said member from a position at one end of said path into a position in which it engages and has its motion arrested by said portion, and mechanism subjected to a selective control effect dependent in magnitude and direction upon the position of said member when its motion is so arrested. 105

2. The combination with an element deflecting about an axis, of means for periodically arresting such deflection comprising a member movable into and out of engagement with said member in a direction transverse to the plane of element deflection, a second member movable in a direction generally transverse to the first mentioned direction into and out of engagement with said element, means for periodically moving said second member between a fixed position in which it is out of engagement with said element into a second position in which it en- 110 115 120 125 130

- gages and has its motion arrested by said element during a period in which the latter is engaged by the first mentioned member, and mechanism subjected to a selective control effect dependent in magnitude and direction upon the position of said second member when its motion is so arrested. 3. The combination with an element deflecting about an axis, of a member pivoted to turn into engagement with a portion of said element about an axis transverse to the deflection path of said portion, yielding means for periodically turning said member about its axis to move said member from a position at one end of said deflection path into the position in which it engages and has its movement arrested by said element, and mechanism subjected to a selective control effect dependent in magnitude and direction upon the position of said member when its motion is so arrested. 4. The combination with an element deflecting about an axis, of a deflection restraining member, means for periodically moving said member into and out of restraining engagement with said element, a second member pivoted to turn about an axis transverse to the first mentioned axis and generally transverse to the direction of movement of the first mentioned member, means for periodically turning said second member from a position out of the path of deflection of said element into a position in which it engages and has its motion arrested by said element, and mechanism subjected to a selective control effect depending in magnitude and direction upon the position of said second member when it engages said element. 5. The combination with a deflecting element, of a member periodically given to and fro movements of equal magnitudes, means actuated by the movements of said member and controlled by the position of said element for temporarily arresting each movement of said member in one direction after an initial portion of said movement varying in magnitude with the deflection of said element, and mechanism selectively actuated in accordance with the position of said member when so temporarily arrested. 6. The combination with a deflecting element, of a member periodically given to and fro movements, means actuated by the movements of said member and controlled by the deflection of said element for temporarily arresting each movement of said member in one direction after an initial portion of the last mentioned movement, mechanism selectively actuated in accordance with the position of said member when its movement is so arrested, and means for actuating the first mentioned means to permit said member to complete its movement in said one direction. 7. The combination with a deflecting element, of a member periodically given to and fro movements, means actuated by each movement of said member in one direction and controlled by the position of said element for temporarily arresting the following return movement of said member after an initial portion thereof varying in magnitude with the position of said element, and mechanism selectively actuated in accordance with the position of said member when its return position is temporarily arrested. 8. The combination with a deflecting element, of a member, means for periodically moving said member back and forth between two positions, means including a part moved by said member into engagement with said element on each such movement of said member in one direction, for temporarily arresting the movement of said member in the opposite direction after an initial portion of the last mentioned movement varying in magnitude with the position of said element when engaged by said part, and mechanism selectively actuated in accordance with the position of said member when its movement is so arrested. 9. The combination with a deflecting element, of a relay mechanism controlled by the deflections of said element and comprising a member periodically moved back and forth between two positions, an element engaging part, means normally connecting said part to said member to share the movements of the latter and yielding to permit said part to be arrested by said element without arresting the movement of said member as the latter moves from one of said positions into the other, means engaging said part and arresting its return movement and that of said member when said part reaches a predetermined return position, means selectively actuated in accordance with the position of said member when its movement is so arrested, and means for disengaging said part and member to permit the completion of the return movement of the latter. 10. The combination with a deflecting element, of a constantly rotating shaft, a second shaft, means connecting said shafts through which the first mentioned shaft intermittently advances and releases said second shaft, means tending to return said second shaft to an initial position when released, and means including a part moved into engagement with said element when said second shaft is advanced for temporarily arresting its return movement after an initial portion thereof dependent in magnitude upon the position of said element. 11. The combination with an element deflecting about an axis, of a shaft extending transversely to said axis and parallel to said element in one position of the latter, a second shaft transverse to the first mentioned shaft, means through which rotative movements of said second shaft give corresponding move- 125 130

ments to the first mentioned shaft, means for giving periodic oscillatory movements to said second shaft, and means including an arm mounted on the first mentioned shaft and moved on each movement of the latter in one direction, into engagement with said element for arresting the movement in the opposite direction of said shaft after an initial portion thereof dependent on the position of 10 said element.

12. The combination with an element deflecting about an axis, of means periodically engaging said element and holding it against deflection, a shaft extending transversely to 15 the pivotal axis of said element and parallel to said element in one position of the latter, means giving said shaft periodical oscillatory movements of constant magnitude, an arm mounted on said shaft, means normally 20 connecting said shaft and arm to cause the latter to share the movements of the shaft, said means yielding to permit further turning movement of the shaft in one direction after said part engages said element, means 25 engaging said arm after a return movement of the latter into a predetermined position and thereby temporarily arresting the return movement of said arm and shaft, means selectively controlled by the position of said shaft 30 when so arrested, and means for periodically adjusting the second mentioned means to permit a completion of the return movement of said shaft.

13. The combination with a deflecting element, of an oscillating shaft, means for periodically holding said shaft in an angular position depending upon the then deflection of said element, a pair of similar cams mounted on said shaft, each comprising a rising portion 40 and a dwell portion, cam engaging elements, means tending to move said elements toward said cams during each period in which the latter is held in said angular position, said cams and elements being so relatively 45 arranged that the dwell of one cam prevents movement of one of said elements toward said cam when the rising portion of the other cam permits the other element to move toward the last mentioned cam, and means selectively 50 actuated by said elements according to their movements toward said cams.

14. The combination with a deflecting element, of a member extending through the plane of deflection of said element and movable along the deflection path of a portion of said element into and out of engagement with said portion, means for periodically moving said member from a position at one end of 55 said path into a position in which it engages and has its motion arrested by said portion, and mechanism subjected to a selective control effect dependent in magnitude and direction upon the displacement of said member from said position when its motion is so arrested.

15. The combination with an element deflecting about an axis, of means for periodically arresting such deflection comprising a member movable into and out of engagement with said member in a direction transverse to the plane of element deflection, a second member movable in a direction generally transverse to the first mentioned direction into and out of engagement with said element, means for periodically moving said second member between a fixed position in which it is out of engagement with said element into a second position in which it engages and has its motion arrested by said element during a period in which the latter is engaged by the first mentioned member, and mechanism subjected to a selective control effect following each movement of said second member into such second position and dependent in magnitude and direction upon the distance between the last mentioned position and said fixed position.

16. The combination with an element deflecting about an axis, of a member pivoted to turn into engagement with a portion of said element about an axis transverse to the deflection path of said portion, yielding means for periodically turning said member about its axis to move said member from a position at one end of said deflection path into the position in which it engages and has its movement arrested by said element, and mechanism subjected to a selective control effect dependent in magnitude and direction upon the magnitude of the movement required to return said member from the last mentioned position into the first mentioned position.

17. The combination with an element deflecting about an axis, of a deflection restraining member, means for periodically moving said member into and out of restraining engagement with said element, a second member pivoted to turn about an axis transverse to the first mentioned axis, means for periodically turning said second member from a position out of the path of deflection of said element into a position in which it engages and has its motion arrested by said element, and mechanism subjected to a selective control effect dependent in magnitude and direction upon the displacement of said second member when it engages said element from the first mentioned position.

18. The combination with a deflecting element, of a member periodically given to and fro movements of equal magnitudes, means actuated by the movements of said member and controlled by the position of said element for temporarily arresting each movement of said member in one direction after an initial portion of said movement varying in magnitude with the deflection of said element, and mechanism selectively actuated in accordance with the magnitude of said portion.

19. The combination with an element hav-
